WALL MOUNTING PLATE FOR A LAMP SUPPORT BRACKET ARM

Henry J. Salvador, Long Beach, Calif., assignor to Eagle
Manufacturing Co., City of Industry, Calif., a corpora-
tion of California

Filed Nov. 29, 1966, Ser. No. 4,850

Term of patent 14 years

(Cl. D48—4)

FIGURE 1 is a perspective view of a wall mounting plate for a bracket support arm showing my new design; and

FIGURE 2 is an enlarged detail view of a portion of the plate of FIGURE 1.

The surface ornamentation fragmentarily shown in FIG. 1 is understood to be continuous through the areas enclosed in dotted lines. The dominant features of my design reside in the portions shown in full lines. The broken line showing of a lamp support bracket arm is for illustrative purposes only. The rear, not shown, is unornamented.

I claim:

The ornamental design for a wall mounting plate for a lamp support bracket arm, substantially as shown and described.
